[57] CLAIM

The ornamental design for electrostatic printer/plotter,
as shown.

DESCRIPTION

FIG. 1 is a perspective view of an electrostatic printer/plotter showing our new design;

FIG. 2 is a front elevational view of the design of FIG. 1;

FIG. 3 is an elevational view of the right side of the
design of FIG. 1;

FIG. 4 is a rear elevational view of the design of FIG. 1;

FIG. 5 is an elevational view of the left side of the
design of FIG. 1;

FIG. 6 is a top plan view of the design of FIG. 1.
